INVENTOR
FRANK GRANT
Joseph J. O'Brien
ATTORNEY

UNITED STATES PATENT OFFICE.

FRANK GRANT, OF WESTFIELD, MASSACHUSETTS.

JACK.

Application filed October 2, 1920. Serial No. 414,340.

To all whom it may concern:

Be it known that FRANK GRANT, a citizen of the United States, residing at 78 Main Street, Westfield, in the county of Hampden and State of Massachusetts, has invented certain new and useful Improvements in Jacks, of which the following is a specification.

This invention relates to improvements in lifting jacks and its leading object is to provide a jack embodying a toggle lifting mechanism operated by a horizontal screw, so that the operator can stand at a distance and without awkward bending from the jack and to operate the same to lift or lower a vehicle.

Another object of the invention is to provide a jack of this type with means for insuring a correct vertical movement upon a standard and means for adjusting sections of the standard to secure a positional lift of the load operating mechanism.

With the above and other objects in view this invention relates to certain new and useful constructions, combinations and arrangements of parts, clearly described in the following specification and fully illustrated in the accompanying drawings, in which:

Figure 1 is a front elevation.

Figure 2 is a top plan view.

Figure 3 is a horizontal sectional view taken on line 3 of Figure 1.

Figure 4 is a detail horizontal sectional view through the standard.

Fig. 5 is a detail longitudinal sectional view through the standard housing.

Fig. 6 is a detail end view of one of the screws and nuts.

Fig. 7 is a detail side elevation of an extension handle.

Referring to the accompanying drawings 5 designates the base of a standard and 6 the upper section thereof. The section 6 has the upper end of a lifting screw 7 swiveled thereto at 8 and this screw has threaded connection with the screw threaded opening 9 of the base 5, which is cut away at 10 so that the screw may be operated, said screw being provided with a head or a large portion 9^a for this purpose.

The standard section 6 is provided with an upstanding bearing lug 11 on the head thereof against which the links 12 and 13 are pivotally connected on one side thereof and on the opposite side the links 14 and 15

are connected by means of a pin or the like 16. The upper ends of the links 12 and 13 are pivotally connected to the nuts 17 and 18 and the upper ends of the links 14 and 15 are pivotally connected to the opposite side 60 of said nuts 17 and 18. To the nuts 17 and 18 the lower ends of the links 19 and 20 are pivotally connected on one side thereof and on the opposite side the links 21 and 22 are pivotally connected to the nuts at their 65 lower ends. The upper ends of the links 19 and 20 are pivotally connected on one side to the depending lug 23 provided on the head 24 and the upper ends of the links 21 and 22 are pivotally connected to said lug 70 23. The lug has a limited rocking action upon the pivot 25 which pivotally secures the links to the lug 23, the upper ends of the guide plates 26 and 27 which are mounted on the ends of said pivot, providing stops 28^a and 29^a to limit the rocking action of said head 24. The upper face of the head 24 is provided with suitable teeth or the like to engage the load.

A right and left screw 29 is threaded 80 through the nuts 17 and 18 so as to move said nuts toward and away from each other when the screw is rotated. This screw is preferably formed hollow and provided with a rectangular bore or a rectangular end so 85 that a crank or the like may be connected thereto to rotate the same. A shaft 31 may be slidably arranged in said screw so that the same may be operated at a distance from the jack. The operating shaft 31 may be 90 provided with a universal joint or the like 32 and with a separable section 33 whereby the same may be easily rotated in angular relation to the screw 29. If desired the standard 5 may be equipped with pockets 95 or the like 34 to receive said screw sections.

The screw 7 is operated to position the head 24 against the load and then the screw 29 is operated so as to move the nuts 17 and 18 toward each other and to force the head 24 and the load thereon upwardly. By rotating the screw 29 in the reverse direction the nuts will be moved apart and due to the action of the connecting links or levers the head 24 will be lowered.

The plates 26 and 27 slide in guideways provided in the standard section 6 and at their lower ends are connected to each other by a spacing block or the like 35. These plates 26 and 27 thus stabilize the vertical 110

movement of the toggle joint comprised by the multiple links and the nuts operated by the right and left screw 29.

Having described my invention, I claim:

- 5 1. A jack consisting of a standard having a vertical guide-way thereon, a pair of plates 30
slidable on the guide-way, bearing provided on said standard at the head thereof, a head pivotally connecting the plates at their upper ends to each other adapted to engage the load, a right and left threaded screw, nuts mounted on said screw in spaced relation to each other to engage them respectively threaded thereon, a pair of links pivotally connected with one of the nuts and 35
pivotally connected with the standard bearing, a pair of links pivotally connected with the other nut and pivotally connected with the standard bearing, a pair of links pivotally connected with the first nut and pivotally connected with the head, a second pair of nuts pivotally connected with the second nut and pivotally connected with the head, a base, and a lifting screw threaded to the base and connected to the lower end 40
of the standard.
10 15 20 25
2. A jack consisting of a standard having

a vertical guide-way thereon, a pair of plates 30
slidable on the guide-way, bearing provided on said standard at the head thereof, a head pivotally connecting the plates at their upper ends to each other adapted to engage the load, a right and left threaded screw, nuts mounted on said screw in spaced relation to each other to engage them respectively threaded thereon, a pair of links pivotally connected with one of the nuts and 35
pivotally connected with the standard bearing, a pair of links pivotally connected with the other nut and pivotally connected with the standard bearing, a pair of links pivotally connected with the first nut and pivotally connected with the head, a second pair of nuts pivotally connected with the second nut and pivotally connected with the head, a base, and a lifting screw threaded to the base and connected to the lower end 40
of the standard.
